UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF TROY, NEW YORK, A CORPORATION OF NEW YORK.

IRONING-PRESS.

940,660.

Specification of Letters Patent. Patented Nov. 23, 1909.

Application filed January 23, 1909. Serial No. 473,854.

To all whom it may concern:

Be it known that I, WILLIAM BARTHOLOMEW, citizen of the United States, residing at Chicago, county of Cook and State of Illinois, have invented certain new and useful Improvements in Ironing-Presses, of which the following is a specification, reference being had therein to the accompanying drawing.

10 This invention relates to an ironing press, and particularly to a structure involving a stationary steam chest and a coöperating movable steam chest.

The invention has for an object to provide 15 a movable steam chest mounted to swing in a vertical plane into and out of alinement with a stationary steam chest and to be moved toward and from the stationary chest.

Another object of the invention is to provide 20 novel and improved means by which the operating lever for swinging the movable chest may be prevented from operation when the steam regulating valves are operated and also to prevent shifting of these 25 valves when the movable chest is swung outward from the fixed chest.

A further object of the invention is to provide 30 a novel construction of cylinder and piston connections for the movable steam chest together with means for controlling the inlet and exhaust of steam from said cylinder.

Other and further objects and advantages 35 of the invention will be hereinafter fully set forth and the novel features thereof defined by the appended claims.

In the drawings:—Figure 1 is a side elevation of the press; Fig. 2 a central vertical section thereof with parts in elevation; Fig. 40 3 is a horizontal section on lines 3—3, Fig. 2; Fig. 4 is a diagram of the valve connections, Fig. 5 is a detail section on line 5—5, Fig. 1.

Like numerals refer to like parts in the 45 several views of the drawings.

The numeral 10 designates the standards which are formed with a yoke or head 11 to which a stationary steam chest 12 of any desired construction is secured, the under 50 face of which coöperates with the movable steam chest 13 to perform the ironing or pressing action. The chest 13 is mounted upon the head plate 14 carried by the piston rod 15 extending from the piston 16 disposed in the cylinder 17 at the base of the

machine. The chest 13 may be padded or clothed if desired and may be also provided with auxiliary devices, such as shirt neck band clamps 18 at one end and a shirt tightener 19 at the opposite end, but these features are no part of the invention. The top of the cylinder 17 is closed by a plate 20 provided with a packing box 21 through which the piston 15 extends. This piston is also provided with a flattened or angular 60 face 22 coöoperating with a similar face in a guide bearing 23 carried by the bracket 24 extending from the cylinder 17. By this means a rotative movement of the piston and chest carried thereby is prevented. The piston 15 is shown as tubular and has disposed therein a steam conducting pipe 25 which discharges at its upper end 26 within the chest 13 and communicates at its lower end 27 with the cylinder so that exhaust steam 70 therefrom is carried to said chest. The head plate 14 is formed with a drain opening 28 to permit the escape of moisture or condensed steam from the chest and the lower end of the piston is also formed with a 80 similar opening 29 to discharge such liquid into the bottom of the cylinder.

The lower portion of the cylinder 17 is formed with laterally extending trunnions or bearings 30 disposed in any desired form 85 of bearing box 31 carried by the base 32 of the standard. One of these trunnions is formed with a steam passage 33 leading inwardly therefrom and upward to communicate with the top of the cylinder 17. The opposite trunnion is formed with a similar inwardly extending passage 34 communicating with the lower portion of this cylinder. In order to provide for an oscillating movement of the trunnions 30 of the cylinder relative to a fixed steam pipe each trunnion is provided with a sleeve or pipe section 35 threaded therein and into a stuffing box socket 36. Each socket has a packing nut 37 threaded thereon to compress the packing 100 38 in the socket to effect a tight joint about the entering steam pipe 39 communicating with the passage 33 to the top of the cylinder and the pipe 40 communicating with the passage 34 to the bottom of the cylinder. 105 Each of the pipes 39 and 40 are provided with a head 72 within the section 35 to prevent longitudinal movement of said pipes.

For the purpose of oscillating the cylinder a segment gear 41 is secured thereto in 110

any desired manner, for instance, to the top plate 20 of the cylinder, as at 42. Coöperating with this gear 41 is a segmental gear 43 mounted at its upper end upon a shaft 44 which is pivoted in the bearing 45 carried by one of the standards. The outer end of this shaft has a handle 46 secured thereto and provided at its free end with a locking pawl 47 of any desired construction adapted to 10 operate with a sector 48 having recesses 49 to receive said pawl. This pawl may be of any preferred construction, for instance pivoted at 50 and coöperating with the pivoted operating lever 51 forming a member of the 15 hand hold upon the lever 46. At the front of the movable chest or the head upon which it is mounted a goods receiving box or tray 52 is suspended from the pivot 53 and formed with a rearwardly extending rigid 20 arm 54 to counterbalance the weight of the front of the tray and cause it to assume and remain in a horizontal position even when the movable chest is swung outward as indicated by dotted lines in Fig. 1.

25 Any preferred arrangement of steam connections for supplying the various parts may be used, but a desirable form thereof is herein illustrated and comprises the feed pipe 55 leading to the fixed chest 12, and 30 the pipe 56 leading downward from said chest to the controlling valves 57 for the cylinder. Each of these valves is provided with a steam inlet 58 from the pipe 56 and with connections 59 and 60 communicating 35 with the steam pipes 39 and 40 respectively, as shown by diagram in Fig. 4. The valves are also each provided with a connection 61 communicating with the exhaust pipe 62 leading to a suitable point of discharge.

40 The valves 57 are simultaneously controlled and shifted by the rods 63 extending from the valve stems parallel to each other to the top of the standard where they are provided with crank arms 64 connected by a 45 plate 65 formed with an operating handle 66. These rods extend through a series of bearings or guides 67 to retain them in proper position. In order to prevent movement of the valves when the operating lever 50 is used to move the swinging chest outward, or the operation of this lever when the valves are used one of the valve rods 63 is provided with a cam or eccentric 68 adapted to coöperate with a contact plate 69 carried by the lever 46. The cam is formed 55 with a flat or straight face 70 which will lie parallel to the side face of the plate 69 when the lever 46 is swung upward to move the chest 13 outward. When in this position it 60 will be obvious that the valve rods cannot be shifted. When the operating lever 46 is in the full line position shown in Fig. 1 and the valves are shifted to control the inlet and exhaust of steam to the cylinder the 65 curved face of this cam is thrown into the

path of the end of the contact plate 69 thus preventing any movement of the lever 46 toward the dotted line position in Fig. 1.

In the control of the valves steam is admitted through one valve to one end of the cylinder and exhausted from the opposite end of the cylinder through the other valve.

Referring to the diagram in Fig. 4 it will be seen that when the levers 64 are in the full line position steam is admitted through pipe 39 to the top of the cylinder at one valve and exhausted through pipe 40 from the bottom of the cylinder at the opposite valve. When the valves are shifted to the dotted line position exactly the opposite operation occurs, or the levers may be so disposed as to cut off steam from both ends of the cylinder and place the face of the locking cam in position to permit operation of the lever for swinging the movable chest and cylinder out of alinement with the fixed chest. Any water of condensation which may collect in the bottom of the cylinder may be withdrawn through the cock connection 71 shown by dotted lines in Fig. 1.

In the operation of the invention the movable chest is swung outward to receive the goods to be ironed or pressed and then swung back into the full line position in Fig. 1 in alinement with the fixed steam chest. At this time the piston is at the lower portion of the cylinder and steam is admitted to that portion while it is exhausted from the upper portion of the cylinder. The body of steam in the cylinder forces the steam chest into pressing position and by passing upward through the pipe within the piston maintains the clothed chest at the proper temperature to quickly dry the clothing therein and secure the most efficient 100 operation. The movable chest is restored to its lowered position by properly shifting the valve rods and during this shifting action the locking cam prevents any operation of the lever controlling the swinging of the cylinder and parts carried thereby. This construction presents means for the most economical use of the steam as all the parts are heated and operated by a single passage or circuit of the steam through the machine, 105 while the control of steam to the cylinder is effected by the shifting of a single handle so that the machine is capable of operation by an ordinary laundry employee. The locking cam upon the valve rod in coöperation with 110 the contact face on the lever effectually prevents accidental or irregular operation of the parts.

Having described my invention and set forth its merits, what I claim and desire to 115 secure by Letters Patent is:

1. In an ironing press, a fixed pressing head, a fluid pressure power cylinder pivotally mounted to oscillate in a vertical plane into and out of alinement with said head,

and a vertically reciprocable piston rod having a coöperating pressing head movable in a straight line toward and from said fixed head.

5 2. In an ironing press, a fixed pressing head, a fluid pressure power cylinder mounted to oscillate in a vertical plane into and out of alignment with said head, a pivotal support for said cylinder disposed at the lower portion thereof, and a vertically reciprocable piston rod having a coöperating pressing head movable in a straight line from the pivotal axis of said cylinder.

10 3. In an ironing press a fixed pressing head, an oscillating and reciprocable coöperating head, and a pivotally mounted fluid pressure motor directly and operatively connected to reciprocate said coöperating head in a straight line from the pivotal axis 15 of said motor.

15 4. In an ironing press, a fixed ironing member, a coöperating ironing member mounted for movement toward and from the fixed member and pivotally supported at its lower portion to swing in a vertical plane 20 into and out of alignment with the fixed member, an operating lever, a gear sector carried upon the shaft of said lever, and a coöperating segment supported upon the 25 movable ironing member.

30 5. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said 35 rod, and power connections with said cylinder for controlling the movement of the piston therein.

40 6. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said 45 rod, power connections with said cylinder for controlling the movement of the piston therein, an operating lever mounted upon the frame, and a connection from said lever to said cylinder for oscillating the latter.

50 7. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said 55 rod, power connections with said cylinder for controlling the movement of the piston therein, an operating lever mounted upon the frame, a connection from said lever to said cylinder for oscillating the latter, and a power controlling valve having an extend-

ed rod provided with operating means therefor.

8. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, power connections with said cylinder 70 for controlling the movement of the piston therein, an operating lever mounted upon the frame, a connection from said lever to said cylinder for oscillating the latter, a power controlling valve having an extended 75 rod provided with operating means therefor, and means carried by said rod for preventing operation of said lever when said rod is shifted in one position.

9. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, power connections with said cylinder 80 for controlling the movement of the piston therein, an operating lever mounted upon the frame, a connection from said lever to said cylinder for oscillating the latter, a power controlling valve having an extended 85 rod provided with operating means therefor, and means carried by said rod for preventing movement thereof when said lever is shifted in position to move the ironing member outward.

10. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, power connections with said cylinder 90 for controlling the movement of the piston therein, an operating lever mounted upon the frame, a connection from said lever to said cylinder for oscillating the latter, a power controlling valve having an extended 95 rod provided with operating means therefor, and means carried by said rod to prevent movement thereof when said lever is shifted in position to move the ironing member outward.

11. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, and power connections with the pivots 110 of said cylinder and leading to the opposite 115 end provided with operating means therefor, and a locking device carried by said rod and having means to prevent movement of said lever when in one position and means to prevent movement of said rod when in another position.

ends thereof to control the movement of the piston therein.

12. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, power connections with the pivots of said cylinder and leading to the opposite ends thereof to control the movement of the piston therein, and controlling means to supply or exhaust through either of said connections.

13. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, power connections with the pivots of said cylinder and leading to the opposite ends thereof to control the movement of the piston therein, and controlling valves connected for simultaneous operation to supply or exhaust through said connections.

14. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, power connections with the pivots of said cylinder and leading to the opposite ends thereof to control the movement of the piston therein, controlling valves adapted to supply or exhaust through said connections, rods extended from said valves and provided with crank arms, and a link connecting said arms and having an operating handle thereon.

15. In an ironing press, a frame having a fixed ironing member mounted thereon, a cylinder pivotally mounted at the lower portion of said frame, a piston disposed within said cylinder and having an upwardly extending rod, a coöperating movable ironing member carried by the upper end of said rod, power connections with the pivots of said cylinder and leading to the opposite ends thereof to control the movement of the piston therein, controlling valves adapted to supply or exhaust through said connections, rods extended from said valves and provided with crank arms, a link connecting said arms and having an operating handle thereon, an operating lever connected to oscillate said cylinder, a contact plate carried by said lever, and a cam mounted upon one of said valve rods and adapted to be moved into the path of said plate.

16. In an ironing press, a frame having a

fixed ironing member mounted thereon, a cylinder pivotally mounted at the lower portion of said frame, a piston disposed within said cylinder and having an upwardly extending rod, a coöperating movable ironing member carried by the upper end of said rod, power connections with the pivots of said cylinder and leading to the opposite ends thereof to control the movement of the piston therein, controlling valves adapted to supply or exhaust through said connections, rods extended from said valves and provided with crank arms, a link connecting said arms and having an operating handle thereon, an operating lever connected to oscillate said cylinder, a contact plate carried by said lever, and a cam mounted upon one of said valves and having a straight face to lie parallel with said plate and a face to contact therewith when shifted.

17. In an ironing press, a frame provided with a steam chest at its upper portion, a coöperating steam chest said coöperating chest being carried by a pivoted power cylinder mounted for movement toward and from the fixed chest in a straight line from the pivotal axis thereof and to swing outward in a vertical plane therefrom, and steam connections with each of said chests.

18. In an ironing press, a frame provided with a steam chest at its upper portion, a coöperating steam chest mounted for movement toward and from the fixed chest and to swing outward in a vertical plane therefrom, steam connections with the chest upon the frame, a cylinder pivoted at the lower portion of said frame and having a piston rod upon which the movable chest is mounted, and a steam connection from said cylinder to said movable chest.

19. In an ironing press, a frame provided with a fixed ironing member, a cylinder pivotally mounted at the base of said frame, a piston having an upwardly extending rod provided with a face to prevent rotary movement thereof, a guide bearing having a coöperating face, and a movable ironing member mounted upon the upper end of said piston.

20. In an ironing press, a frame provided with a fixed ironing member, a cylinder pivoted at the lower portion of said frame and having steam passages extending through the trunnions thereof, a piston disposed in said cylinder, a tubular piston rod extending outward from said piston, and a steam chest secured to the upper end of said rod.

21. In an ironing press, a frame provided with a fixed ironing member, a cylinder pivoted at the lower portion of said frame and having steam passages extending through the trunnions thereof, a piston disposed in said cylinder, a tubular piston rod extending outward from said piston, a steam chest secured to the upper end of said rod and hav-

ing a drain opening communicating therewith, and a feed pipe extended within said rod from the cylinder to said chest.

22. In an ironing press, a frame provided with a fixed ironing member, a cylinder pivoted at the lower portion of said frame and having steam passages extending through the trunnions thereof, a piston disposed in said cylinder, a tubular piston rod extending outward from said piston, a steam chest secured to the upper end of said rod and having a drain opening communicating therewith, a feed pipe extended within said rod from the cylinder to said chest, and a 15 segmental rack and gear for oscillating said cylinder.

23. In an ironing press, a yoke frame having at its upper portion an ironing member, a cylinder pivotally mounted at the lower portion thereof and having steam passages extending through its trunnions, a piston and rod carried by said cylinder, an ironing member carried by the free end of said rod, feed pipes leading to the opposite cylinder 25 trunnions, and a packing to permit rotative movement of said trunnions upon said pipes.

24. In an ironing press, a yoke frame having at its upper portion an ironing member, a cylinder pivotally mounted at the lower portion thereof and having steam passages extending through its trunnions, a piston and rod carried by said cylinder, an ironing member carried by the free end of said rod, feed pipes leading to the opposite cylinder 35 trunnions, a sleeve secured to each of said trunnions and extending outward therefrom, a packing socket mounted upon said sleeve, and a packing nut mounted upon said socket to compress packing therein.

40 25. In an ironing press, a yoke frame having at its upper portion an ironing member, a cylinder pivotally mounted at the lower portion thereof and having steam passages extending through its trunnions, a piston and rod carried by said cylinder, an ironing member carried by the free end of said rod, feed pipes leading to the opposite cylinder 45 trunnions, a sleeve secured to each of said trunnions and extending outward therefrom, a packing socket mounted upon said sleeves, a packing nut mounted upon said socket to compress packing therein, and a head secured upon the pipe end within said sleeve.

55 26. In an ironing press, a frame, a fixed ironing member carried thereby, a cylinder pivotally mounted in said frame and provided with steam passages extending through the trunnions, and communicating with opposite ends of said cylinder, an ironing member carried by said cylinder, controlling valves each having a port connected to one of said trunnions, a steam feed pipe communicating with each of said valves, an

exhaust pipe extending from each of said valves, and means connecting said valves for simultaneous operation to exhaust from one trunnion as steam is fed to the opposite one.

27. In an ironing press, a frame, a cylinder pivotally mounted in said frame and provided with steam passages extending through the trunnions, and communicating with opposite ends of said cylinder, an ironing member carried by said cylinder, controlling valves each having a port connected to one of said trunnions, a steam feed pipe communicating with each of said valves, an exhaust pipe extending from each of said valves, means connecting said valves for simultaneous operation to exhaust from one trunnion as steam is fed to the opposite one, and a steam chest carried by said frame and communicating with said feed pipe.

28. In an ironing press, a frame, a cylinder pivotally mounted in said frame and provided with steam passages extending through the trunnions, and communicating with opposite ends of said cylinder, an ironing member carried by said cylinder, controlling valves each having a port connected to one of said trunnions, a steam feed pipe communicating with each of said valves, an exhaust pipe extending from each of said valves, means connecting said valves for simultaneous operation to exhaust from one trunnion as steam is fed to the opposite one, a steam chest carried by said frame and communicating with said feed pipe, and a steam feed connection extending from said cylinder to the ironing member carried thereby.

29. In an ironing press, a frame, an ironing member carried thereby, a coöperating ironing member mounted at the lower portion of the frame for oscillation in a vertical plane and for reciprocation toward and from the ironing member carried thereby, an operating lever pivoted upon the frame and connected to oscillate said movable ironing member, a segmental rack carried by the frame, and a pawl upon said lever coöperating with said rack.

30. In an ironing press, a frame, an ironing member carried thereby, a coöperating ironing member mounted at the lower portion of the frame for oscillation in a vertical plane and for reciprocation toward and from the ironing member carried thereby, an operating lever pivoted upon the frame and connected to oscillate said movable ironing member, a segmental rack carried by the frame, a pivoted lever pawl mounted upon said lever, and a coöperating hand piece upon the lever to engage the tail of said pawl.

31. In an ironing press, a frame, an ironing member carried thereby, a coöperating

ironing member pivotally mounted at the lower portion of the frame for oscillation in a vertical plane, an operating lever pivoted upon the frame and connected to oscillate 5 said movable ironing member, a segmental rack carried by the frame, a pivoted lever pawl mounted upon said lever, a segmental contact plate extended laterally from said lever, and shiftable means adapted to be 10 thrown into the path of said plate to prevent movement of said lever.

32. In an ironing press, a frame, a fixed ironing member carried thereby, a movable ironing member pivotally mounted at the 15 lower portion of the frame to swing in a vertical plane, a receiving shelf pivoted to the upper portion of said movable member and extended outward therefrom, and means for

counterbalancing the extended portion of said shelf.

33. In an ironing press, a frame, a fixed ironing member carried thereby, a movable ironing member pivotally mounted at the lower portion of the frame to swing in a vertical plane, a receiving shelf pivoted to 25 the upper portion of said movable member and extended outward therefrom, and a rearwardly extended rod from said shelf having a weight disposed thereon.

In testimony whereof I affix my signature 30 in presence of two witnesses.

WILLIAM BARTHOLOMEW.
